ATTORNEY

UNITED STATES PATENT OFFICE.

JAMES I. RICHEY, OF CINCINNATI, OHIO.

PREHEATER.

Application filed December 14, 1921. Serial No. 522,425.

To all whom it may concern:

Be it known that I, JAMES I. RICHEY, a citizen of the United States, residing at Cincinnati, in the county of Hamilton and State 5 of Ohio, have invented certain new and useful Improvements in Preheaters, of which the following is a specification.

My invention relates to devices for heating the charge of an internal-combustion engine before starting and in the early part 10 of its operation. Its object is to provide a more simple, more readily installed device of this character. A further object is to simplify the operation and add to the efficiency of such devices. Other objects will appear in the course of the ensuing description.

I attain these objects by the device illustrated, for example, in the accompanying 20 drawing, in which—

Figure 1 is a partial side elevation of an internal-combustion engine equipped with a device embodying my invention, the device being represented as with its near side 25 broken away to reveal the interior operation;

Fig. 2 is a similar view of a modification, the only parts of the engine disclosed, however, being the intake pipe and its carburetor connection;

Fig. 3 is a view corresponding to a section on the transverse plane of the line 3—3 of Fig. 2, showing another modification;

Fig. 4 is a view corresponding to Fig. 2, 35 showing another modification;

Fig. 5 is a section on the plane of line 5—5, Fig. 4; and

Fig. 6 is a detail plan view of the cover plate.

In the example of Fig. 1 the preheater 40 comprises a hollow body 1 formed by two inversely assembled sections 2 and 3 having flanges 4 and 5, respectively, meeting nearly on the median transverse plane of the engine 45 fuel-intake pipe 6, and thus surrounding the lower flanged end part 7, upwardly extending stem 8, and lengthwise extending branches 9 of this pipe. The top part of the body 1 may be understood from Fig. 5, 50 which example has the same arrangement. Each section 2 and 3 has an inturned rim 10 or 11 integral with its main upright wall, and upon these rims is screwed a cover plate 12 between the upright parts 13 of the pipe 55 branches 9 where they extend out of the preheater hollow body. The flanges 4 and 5 are

secured together by small bolts 14 and nuts 15 at intervals, clamping these parts of the body together. Also, the cover plate 12 has near its opposite ends out near its front edge, openings 16 upwardly from which lead pipes 17.

The lower part of the section 2 has a flat rear wall 18; and centrally of this flat wall is an opening to register with the meeting 60 openings of the intake pipe 6 and the carburetor 19 with the surrounding portions of the flat wall between the flanges 20 and 21 of the pipe 6 and the carburetor 19, respectively, with suitable gaskets 22 and 23 flanking the wall, so that when the intake pipe and carburetor junction is completed, this 65 part of the hollow body of the preheater has a liquid and gas-tight closure around the intake passage. The extreme bottom of the 70 hollow body is in the form of a pocket 24, formed half in each section 2 or 3 with respective flanges continued around under it; and immediately above this pocket 24 the outer section 3 has an opening 25 closed by 75 a swinging cover 26.

It will be understood that suitable gaskets are placed between the flanges 4 and 5. Also, I prefer that the top plate 12, when screwed to the hollow body, rest snugly along on top 80 of the longitudinal branches 9 of the intake pipe. This relation of the parts, with the sections 2 and 3 and the cover plate 12 closely embracing the upright parts 13 of the branches, and with the bottom part tightly 85 clamped between the intake pipe and carburetor flanges 20 and 21, effectively prevents vibration of the device, which is a 90 very important consideration on vehicle engines especially, where the vibration due 95 to the vehicle travel is added to that of the engine itself.

As shown in Fig. 1, the pocket 24 at the bottom receives a combustible fluid through the opening 25, which may be ignited therethrough; this combustion passing 100 up and around the intake pipe 6 and heating the charge therein so that when the charge reaches the cylinder it is readily ignited. The pipes 17 lead up and then forwardly and rearwardly, respectively, along 105 side the exhaust pipe 27 of the engine, the front one entering near the forwardmost branch 28 of the exhaust pipe, and the rear one entering the rear part of the exhaust 110 pipe, preferably to the rear of the last one of the branches 29 of this pipe. These pipes

17 conduct the products of combustion from the interior of the pre-heater hollow body into the exhaust pipe 27 before starting; and after starting, the engine exhaust is led into 5 the preheater body through the front pipe 17 and then out by the rear pipe 17 into the exhaust pipe beyond the engine connection, where the passage of the exhaust acts inductively to promote and stimulate this 10 draft of the engine exhaust through the preheater, continuing to preheat the fuel entering through the manifold while the engine is running. This promotion of the draft by the engine exhaust also is valuable 15 in maintaining the heating effect of any combustion still taking place in the preheater after the engine is started, thus preventing it from missing fire in its early stages of operation.

20 The cover plate 12 also has near its middle and near its front an opening 30 closed by a cover 31 for pouring fuel in, to run over the manifold. This may be used instead of the opening 25; or the fuel may be 25 poured in at this top opening, but ignited through the lower opening 25.

In the modification of Fig. 2, the intake pipe 6' has the lengthwise branches 9' and upstanding branches 13', but its stem 8' is 30 short, with a downwardly facing flange 20', and the carburetor connection comprises the elbow 21' with an upper flange meeting the stem flange 20' and a lower flange to connect with the carburetor body, not shown 35 in this figure, but which will be understood from Fig. 1. This is an intake pipe and carburetor arrangement found in some makes of engines. My preheater body 1' accordingly is modified, having the flat wall 40 of the previous example absent, but having the flat bottom 18' with the proper opening, and fitting between the pipe and elbow flanges with the gaskets 22' and 23'. Also, in this example, there is but one section, 45 with a fully open top, similar to that of my Patent No. 1,362,353, issued December 14, 1920. In this example I have taken occasion to show another method of using the combustible liquid fuel; the hollow body containing a quantity of sand 32 or similar 50 friable incombustible body, into which a quantity of the combustible liquid is poured, and then ignited. The combustion thus is slower and steadier, with the fuel distributed 55 throughout the interstices of the sand 32 or the like. It will be understood that this method may be used in the example of Fig. 1.

In Fig. 3, the device is similar to that of 60 Fig. 2 in its lower parts, but the inner wall of the body 1'' has an opening and is clamped between the upper end of the fuel-intake pipe 6'' and the engine cylinder, with suitable gaskets, the same as the bottom connects with the lower end of the pipe 6'' and

the carburetor connection 21''; the intake pipe 6'' of this engine taking the form of an elbow. The body sections do not meet in an upright plane as in Fig. 1, but take the forms of the lower main body part 2' 70 and the top part 3', meeting in a horizontal plane entirely above the intake pipe 6'', with flanges 4' and 5', respectively, secured together by the small bolts 14' and 15' at intervals around the four sides of the structure. It will be understood that the carburetor connection here is the same as that of Fig. 2, with the elbow 21'' meeting the bottom flange of the intake pipe 6'' and thus clamping the bottom of the body part 2' as 75 in Fig. 2, and this elbow 21'' having a lower flange to connect with the carburetor body at the remote end thereof as positioned in this view, where these connections are hidden. Also it will be understood that the intake pipe 6'' may have a plurality of branches into the cylinder; the peculiarity being that, whatever the number of these branches, the junction of the sections 2' and 3' is entirely above them. In this example, 80 the body contains a body of hot water poured into it through the neck 30' in the middle of the top part 3', similar to that in Fig. 1, to heat intake pipe 6'' and the fuel charge passing therethrough when starting 85 the engine. The water is drained off through the cock 33 after its heat has been utilized. With clear water this draining is a necessary precaution in freezing weather; but anti-freezing mixtures may be used. For 90 instance, a quantity of the anti-freezing substance can be placed in the preheater, to be absorbed by successive charges of hot water until depleted.

In Figs. 4 and 5 the preheater body 1^a is 95 formed of inversely arranged sections 2^a and 3^a meeting in an upright plane forward of the fuel-intake pipe 6^a, with bolted-together and gasketed flanges 4^a, 5^a, 14^a and 15^a, similar to those of Fig. 1; but the lower arrangement is like that of Figs. 2 and 3 and the parts thereof are correspondingly numbered. The device of this example is shown as filled with hot water; but it will be understood that it may be used as the devices of 100 Figs. 1 and 2, respectively, with or without the flues 17 of Fig. 1, for burning fuel in the body.

Any of the examples is very readily 105 stamped and pressed from sheet metal, which makes them economical to produce. At the same time, they are readily assembled and installed on the engines by persons of little mechanical skill; and the methods of use are simple and easily understood by the 110 engine users, and not dangerous. Also, with the device made of relatively thin sheet metal, if the hot-water method is used, and the water is left after the engine is stopped 115 for a while in freezing temperature, the 120

yielding walls of the preheater body absorb the expansion of the freezing water, without cracking, as cast-iron containers do, and without causing breakage of the intake-pipe, which usually is of cast-iron.

I have disclosed numerous examples of the application of my invention to different engines, or for different methods of heating; but other modifications may occur under

10 varying conditions of engine design or use. Therefore, while certain constructional details are deemed preferable in connection with my invention, and these have been specifically disclosed herein, as is required,

15 I do not wish to be understood as being limited to such precise showing and description, but what I claim as new and desire to secure by Letters Patent is:

1. A preheater comprising a hollow body 20 to surround an internal-combustion-engine fuel-intake pipe and having a part to be clamped between said pipe and an adjacent connected part.

2. A preheater comprising inversely assembled sections forming a hollow body to surround an internal-combustion-engine fuel-intake pipe and having a part to be clamped between said pipe and an adjacent connected part.

3. A preheater comprising a hollow body to surround an internal-combustion-engine fuel-intake pipe, having an upper part with distinct openings whereby said part embraces distinct upwardly extending branches of said pipe, and having a part to be clamped between said pipe and an adjacent connected part.

4. A preheater comprising inversely assembled sections forming a hollow body to surround an internal-combustion-engine fuel-intake pipe, having an upper part with distinct openings whereby said part embraces distinct upwardly extending branches of said pipe, and having a part to be clamped between said pipe and an adjacent connected part.

5. A preheater comprising a hollow body to surround an internal-combustion-engine fuel-intake pipe, having an upper part with distinct openings whereby said part embraces distinct upwardly extending branches of said pipe and lies closely along and against lengthwise top parts of said pipe, and having a part to be clamped between said pipe and an adjacent connected part.

6. A preheater comprising inversely assembled sections forming a hollow body to surround an internal-combustion-engine fuel-intake pipe and having a part to be clamped between said pipe and an adjacent connected part, said sections meeting substantially in an upright plane.

7. A preheater comprising inversely assembled sections with meeting flanges 65 clamped together, forming a hollow body to surround and extend over an internal-combustion-engine fuel-intake pipe with part of said body against said intake pipe and another part of said body rigidly clamped between said intake pipe and an adjacent connected part.

8. A preheater comprising inversely assembled sections with meeting flanges 70 clamped together, forming a hollow body to surround an internal-combustion-engine fuel-intake pipe and with part of said body rigidly clamped between said intake pipe and an adjacent connected part.

9. A preheater comprising inversely assembled sections with meeting flanges 80 clamped together, forming a hollow body to surround and extend over an internal-combustion-engine fuel-intake pipe, with the over-extending part of said body against said intake pipe and a lower part of said body rigidly clamped between said intake pipe and an adjacent connected part.

10. A preheater comprising inversely assembled sections forming a hollow body to 90 surround an internal-combustion-engine fuel-intake pipe, having an upper part with an elongated opening whereby said part embraces distinct upwardly extending branches of said pipe, and a cover to lie closely along and against lengthwise top parts of said pipe, between said branches.

11. A preheater comprising inversely assembled sections forming a hollow body to surround an internal-combustion-engine 100 fuel-intake pipe, having an upper part with an elongated opening whereby said part embraces distinct upwardly extending branches of said pipe, and having a part to be clamped between said pipe and an adjacent connected 105 part, said sections meeting substantially in an upright plane transverse to said lengthwise part of said pipe, and a cover to lie closely along and against lengthwise parts of said pipe, between said branches, over 110 said elongated opening.

12. In combination with an internal combustion engine having a fuel-intake pipe and an exhaust pipe, a preheater comprising a hollow body to surround said fuel-intake pipe, and a plurality of combustion-product-outlet pipes leading from the upper part of said body into said engine exhaust pipe at opposite sides of a final one of a plurality of branches of said exhaust pipe, whereby 115 passage of the engine exhaust acts inductively at one of said combustion-product-outlet pipes to stimulate a draft of part of the engine exhaust through said hollow body after the engine is started.

JAMES I. RICHEY.
